UNITED STATES PATENT OFFICE.

ERNON V. OLIVER, OF PASADENA, CALIFORNIA.

WATER STILL.

Application filed December 29, 1923, Serial No. 683,358. Renewed June 14, 1928.

This invention relates to improvements in water stills and more particularly to the domestic type such as constitute the subject matter of my co-pending applications, filed December 4, 1923, Serial Nos. 678,450 and 678,451, and the present invention relates more specifically to the condenser of such a still and to certain correlated features of the condenser and the receiver, and in this connection, in order to render clear the meaning of the terms employed, it may be stated that in the co-pending applications the still, in each instance, comprises a generator in which the water is converted into steam, a condenser in which the steam is condensed, and a receiver which is interposed between the generator and the condenser and to which is delivered the water of condensation.

The primary object of the present invention
20 is to provide a condenser so constructed that
a more thorough circulation of the cooling
water may be had thereby rendering the ap-
paratus more efficient and considerably ex-
pediting the process of distillation.

25 Another object of the invention is to provide for circulation of the cooling water in such manner as to bring about heat exchange between the steam and water in the most effective manner.

30 In the accompanying drawings:

Figure 1 is a vertical diametric sectional view through one form of condensing and receiving apparatus embodying the invention;

Figure 2 is a top plan view of the condensing apparatus;

Figure 3 is a top plan view of the receiving apparatus.

Figure 4 is a top plan view of a modified form of the condensing apparatus.

40 As before pointed out, each of the stills disclosed in my said co-pending applications comprises a generator in which the water is converted into steam, and inasmuch as the generator constitutes no part of the present invention, only a portion thereof is illustrated in the drawings and is indicated by the numeral 1. Upon the casing or shell of the generator there is supported a receiver which is indicated in general by the numeral 2 and 45 which will presently be more specifically described.

The condenser embodying the invention is indicated in general by the numeral 3 and the same is supported upon the casing of the receiver 2. The condenser 3 comprises a wall

4 which, in that embodiment of the invention illustrated in Figures 1, 2 and 3 of the drawings, is of cylindrical form, the casing or shell of the condenser being open at its top as clearly shown in Figure 1 of the drawings and the wall 4 being supported by an annular bottom 5 which surrounds a cylindrical wall 6 having a depending lower portion 7 which extends downwardly beneath the annular bottom 5 and is provided with an off-set flange 8 adapting it to be removably fitted upon the top of the receiver casing 2. A cylindrical wall 9 is arranged concentrically with relation to the wall 6 and is surrounded by the latter wall and supported by an annular top wall 10 which extends between the said walls 6 and 9. The space between the walls 4 and 6 constitutes a cooling chamber which is indicated by the numeral 11, and the space between the walls 6 and 9 constitutes a condensing chamber indicated by the numeral 12. For the escape of noxious gases, vent pipes 13 are arranged upon the top wall 10 of the condensing chamber 12 and it will be observed by reference to Figure 1 that the said wall 10 is located in a plane somewhat below the open top of the shell defined by the wall 4, the vent tubes 13 extending upwardly from the said wall 10 and likewise terminating at their open upper ends below the plane of the top of the said shell. The lower ends of the vent tubes 13 are placed in communication with the upper portion of the condensing chamber 12 through small openings 14 which are formed in the said wall 10 as shown in Figure 1. The numeral 15 indicates in general a condensing chamber which comprises a conical shell 16 which at its base is united to and supported by the lower end of the wall 9 of the condensing chamber 12, the said shell 16 projecting upwardly into the cylindrical cooling chamber 17 which is defined by the said wall 9, it being evident that the wall 9 is common to both the condensing chamber 12 and the cooling chamber 17. The upper end of the conical shell 16 terminates at a point below the plane of the top wall 10 of the condensing chamber 12 so that water filling the chambers 11 and 17 will surround and cover all three walls of the said condensing chamber 12, this chamber being open at its bottom to communicate with the space above the receiver 2.

Arranged within the cooling chamber 17 is a circulating chamber which is indicated in 110

general by the numeral 18 and which comprises, in that form of the invention shown in Figures 1, 2 and 3 of the drawings, a cylindrical shell 19 which is disposed at its lower 5 portion to fit about the upper portion or apex of the conical shell 16 constituting the condensing chamber 15, the lower edge of the wall of the shell 19 being suitably united in a water-tight manner to the outer side of the 10 wall of the said shell 16. The shell 19 is open at its top and its upper end terminates in a plane above the plane of the top wall 10 of the condensing chamber 12 and below the plane of the open top of the shell 4. Openings 20 are 15 formed in the wall of the shell 19 immediately above the juncture of the wall with the wall of the shell 16 and serve a purpose to be presently explained.

In order that water or other cooling fluid 20 may be supplied to the condenser, an annular pipe 21 is arranged within the bottom of the cooling chamber 11 and is provided in its upper side with perforations 22 through which water may be discharged, water being supplied to the said pipe by a supply pipe 23 leading from any suitable source of supply and connected to the said pipe 21 through the wall of the shell 4, a cut-off valve 24 being interposed in the said pipe 23. In order that 30 the pipe 21 may be flushed when occasion requires, and thus cleared of any sediment which may accumulate therein, the said pipe is preferably provided at its side opposite the side at which the pipe 23 is connected, with an up- 35 standing nipple 25 into which is removably fitted a closure plug 26, the plug 26 being designed to be removed when the pipe is to be flushed.

An overflow pipe 27 has its inlet end fitted 40 through the wall of the circulating chamber 18 and preferably downturned as indicated by the numeral 28, and this pipe extends diametrically across the open upper portion of the condenser shell 4 and through the wall of 45 the said shell and is thence led downwardly as indicated by the numeral 29 and is positioned to discharge into a receiving funnel or the like 30 which is provided with a discharge pipe 31. In the structures shown in my above- 50 referred to co-pending applications, the pipe 31 leads to the well of the generator so that water overflowing from the condenser through the pipe 27 will be delivered through the pipe 31 to the said generator where it will be converted into steam. It is preferable to provide 55 a second overflow pipe indicated by the numeral 32 which pipe likewise leads at its intake end through the wall of the circulating chamber 18 and at its other end is led through 60 the wall of the shell 4, this pipe being provided with a cut-off valve 33 which may be adjusted to permit of overflow of water from the circulating chamber 18 to a suitable receptacle such as the ordinary kitchen sink.

65 The receiver 2 heretofore referred to does

not differ materially from the receivers of the stills shown in my said co-pending applications, except in one respect which will now be explained. The receiver comprises a cylindrical shell 34 open at its top and bottom and 70 communicating at its bottom with the generator 1 to receive the steam generated therein and open at its top to communicate with the open bottom of the condenser. Arranged within the shell 34 is a receiving pan 35 which 75 is of inverted conical form and comparatively shallow, and upstanding from the bottom of this pan and opening therethrough are short tubes 36 through which steam generated in the generator 1 may issue and be discharged into the upper portion of the receiver 2 and the lower portion of the condenser. A distilled water outlet pipe 37 leads from the extreme 80 lower portion of the pan 35 and through the wall of the shell 34 of the receiver and serves to deliver the distilled water to any suitable receptacle.

It will now be evident that when water is supplied through the pipe 23, it will rise in the cooling chamber 11 and overflow into the cooling chamber 17 thus cooling the walls of the condensing chamber 12. The water can only leave the chamber 17 by way of the openings 20 in the lower portion of the circulating chamber 18 because of the fact that the upper 90 end of this chamber is located in a plane above the overflow pipes 27 and 32. Inasmuch as the intake ends of the pipes 27 and 32 are located within the circulating chamber 18, the water supplied to the condenser can only leave the condenser after having passed upwardly through the cooling chamber 11, downwardly through the cooling chamber 17, and finally upwardly through the circulating chamber 18. Therefore, the water supplied to the condenser 100 is caused to circulate over the surfaces of the walls of the condensing chambers 12 and 15 in a manner to most effectually cool the walls and thereby most effectually condense the steam which is delivered into the chambers 110 12 and 15 through the tubes 36 upon the receiving pan 35. The water, condensing upon the walls of the condensing chambers 12 and 15 will of course drip from these walls into the said pan 35 and will be delivered from the 115 pan by way of the pipe 37.

The foregoing description has been directed more particularly to the form of the invention shown in Figures 1, 2 and 3 of the drawings and by reference to Figure 4 it will be observed that this form is identical with the form previously described except that the chamber 15 is of pyramidal form and the shells of the generator, receiver, and condenser are therefore of rectangular form. Likewise in this modified form, the vent pipes 120 38 rise from the top or ridge of the condensing chamber to a point above the water level in the condenser.

Parts illustrated in Figure 4 of the draw- 130

- ings and corresponding to those illustrated in the other figures of the drawings and particularly Figure 2, are indicated by like reference numerals with the addition of the suffix "a."
- 5 As previously stated, the modified structure shown in Figure 4 is substantially identical with Figures 1, 2 and 3 except that the apparatus is of general rectangular form instead of cylindrical so that Figure 1 of the drawings corresponds in practically every detail with what is shown in Figure 4, when Figure 4 is viewed in section.
- It will be noted that certain of the vent tubes 36 are arranged in a circular series immediately beneath the chamber 12 and that the other tubes are distributed over the surface of the pan within this circle.
- Having thus described the invention, what is claimed as new is:
- 20 1. A still condenser comprising an upwardly tapered condensing chamber, a wall surrounding the said chamber and constituting, in combination with the wall of the condensing chamber, a cooling water chamber, means for supplying water to the cooling water chamber, and means for effecting circulation of the water in an upward direction over the surface of the wall of the condensing chamber, the said means comprising a circulating chamber surrounding the upper portion of the condensing chamber and having water inlet openings near its bottom. 25
2. A still condenser comprising an upwardly tapering condensing chamber, a cooling water chamber within which the condensing chamber is located, the condensing chamber being open at its bottom and constituting the bottom of the cooling water chamber within which it is located, a cooling water circulating chamber surrounding and enclosing the upper portion of the condensing chamber and having openings in its wall near its bottom, means for supplying water to the cooling water chamber exteriorly of the circulating chamber whereby the water will flow downwardly about the circulating chamber and thence upwardly along the lower portion of the wall of the condensing chamber, through the said openings in the wall of the circulating chamber, and upwardly along the upper portion of the wall of the condensing chamber, and an overflow leading from the interior of the circulating chamber. 40
3. A still condenser comprising an upwardly tapered condensing chamber open at its bottom, a second condensing chamber surrounding the first mentioned chamber and likewise open at its bottom, the lower portion of the wall of the first mentioned condensing chamber being united to the lower portion of the inner wall of the second mentioned condensing chamber whereby to provide between the chambers a cooling water chamber closed at its bottom and open at its top, a cooling water chamber surrounding the second mentioned condensing chamber, means for supplying water to the last mentioned cooling water chamber whereby to overflow into the first mentioned cooling water chamber, the said means comprising a continuous pipe extending about the bottom of the last mentioned cooling water chamber, and a water supply pipe in communication therewith, the first mentioned pipe having outlet openings for the water supply thereto. 45
4. A still condenser comprising an upwardly tapered condensing chamber open at its bottom, a second condensing chamber surrounding the first mentioned chamber and likewise open at its bottom, the lower portion of the wall of the first mentioned condensing chamber being united to the lower portion of the inner wall of the second mentioned condensing chamber whereby to provide between the chambers a cooling water chamber closed at its bottom and open at its top, a cooling water chamber surrounding the second mentioned condensing chamber, means for supplying water to the last mentioned cooling water chamber whereby to overflow into the first mentioned cooling water chamber, the said means comprising a continuous pipe extending about the bottom of the last mentioned cooling water chamber, and a water supply pipe in communication therewith, the first mentioned pipe having outlet openings for the water supplied thereto, a nipple extending upwardly from the said continuous pipe, and a removable closure fitted into the upper end of the nipple whereby the said pipe may be flushed upon removal of the said closure. 50
5. In a still, a condenser comprising a hollow upwardly tapering condensing chamber open at its bottom, a second condensing chamber surrounding and enclosing the first mentioned chamber and likewise open at its bottom, a cooling water chamber enclosing the condensing chambers, means for supplying water to the cooling water chamber, and a receiver beneath the condenser comprising a shell open at its top and in communication with the space below the open bottoms of the condensing chambers, a receiving pan within the shell of the receiver inclined downwardly toward its center, an outlet pipe leading from the low point of the pan through the shell of the receiver, a plurality of steam tubes upstanding from the pan and opening at their lower ends through the pan and arranged in a series beneath the open bottom of the second-mentioned condensing chamber, and a plurality of steam tubes upon the pan opening at their lower ends through the said pan and located beneath the open bottom of the first-mentioned condensing chamber. 55
6. A still condenser comprising an up- 60

wardly tapered condensing chamber open at its bottom, a second condensing chamber surrounding the first mentioned chamber and likewise open at its bottom, the lower portion of the wall of the first mentioned condensing chamber being united to the lower portion of the inner wall of the second mentioned condensing chamber, whereby to provide, between the chambers, a cooling water 10 chamber closed at its bottom and open at its top, and means for effecting circulation of water in the cooling water chamber in an upward direction over the surface of the wall of the condensing chamber, said means 15 comprising a circulating chamber surrounding the upper portion of the condensing chamber and having water inlet openings near its bottom.

7. A still condenser comprising an upwardly tapered condensing chamber open at its bottom, a second condensing chamber surrounding the first mentioned chamber and likewise open at its bottom, the lower portion of the wall of the first mentioned condensing chamber being united to the lower portion of the inner wall of the second mentioned condensing chamber whereby to provide, between the chambers, a cooling water 20 chamber closed at its bottom and open at its top, means for supplying cooling water to the said cooling water chamber, means for effecting circulation of the water in an upward direction over the surface of the wall of the condensing chamber, said means 25 comprising a circulating chamber surrounding the upper portion of the condensing chamber and having water inlet openings near its bottom, and overflow pipes having their intake ends in communication with the said 30 circulating chambers.

8. A still condenser comprising an upwardly tapered condensing chamber open at its bottom, a second condensing chamber surrounding the first mentioned chamber and likewise open at its bottom, the lower portion of the wall of the first mentioned condensing chamber being united to the lower 45

portion of the inner wall of the second mentioned condensing chamber whereby to provide, between the chambers, a cooling water 50 chamber closed at its bottom and open at its top, means for supplying cooling water to the said cooling water chamber, means for effecting circulation of the water in an upward direction over the surface of the wall 55 of the condensing chamber, said means comprising a circulating chamber surrounding the upper portion of the condensing chamber and having water inlet openings near its bottom, overflow pipes having their intake ends 60 in communication with the said circulating chamber and air vent tubes leading upwardly from the closed top of the second mentioned condensing chamber.

9. A still condenser comprising an upwardly tapered condensing chamber open at its bottom, a second condensing chamber surrounding the first mentioned chamber and likewise open at its bottom, the lower portion of the wall of the first mentioned condensing chamber being united to the lower portion of the inner wall of the second mentioned condensing chamber whereby to provide, between the chambers, a cooling water 65 chamber closed at its bottom and open at its top, a cooling water chamber surrounding the second mentioned condensing chamber, means for supplying water to the last mentioned cooling water chamber whereby to overflow into the first mentioned water 70 chamber, and means for effecting circulation of the water in an upward direction over the surface of the wall of the first mentioned condensing chamber, the said means comprising a cylindrical circulating chamber surrounding the upper portion of the first mentioned condensing chamber and having water 75 inlet openings near its bottom, and an overflow pipe in communication at its intake end with the upper portion of the circulating 80 chamber.

In testimony whereof I affix my signature.

ERNON V. OLIVER. [L.S.]
